UNITED STATES PATENT OFFICE.

SAUL PRAGER, OF NEW YORK, N. Y.

DESIGN FOR A BROOCH OR PIN.

SPECIFICATION forming part of Design No. 25,632, dated June 16, 1896.

Application filed February 8, 1896. Serial No. 578,612. Term of patent 31 years.

To all whom it may concern:

Be it known that I, SAUL PRAGER, a subject of the Emperor of Austria-Hungary, residing at New York, in the county of New York and State of New York, have invented a certain new and original Design for a Brooch or Pin; and I do hereby declare the following to be a full, clear, and exact description of the design, such as will enable others skilled in the art to which it appertains to make and use the same, reference being had to the accompanying drawings, and to figures of reference marked thereon, which form a part of this specification.

Figure 1 is a front end elevation showing my design; and Fig. 2 is a side or face view of the same, these views being deemed necessary to fully illustrate my design.

The leading features of my design consist in a bicycle having a woman dressed in "bloomers" secured thereon, and having the representation of jewels in the form of small circles 6, around the rims of the wheel of the bicycle, and circles 7 all over the clothing of the woman, as shown in Fig. 2.

1 represents a safety-bicycle on which is

permanently secured a woman 2, dressed in bloomers and grasping the handles 3 of the bicycle 1 with her hand 4. On the sides 5 of the pneumatic tire and entirely around the 30 same are inserted or set precious stones 6, and stones 7 are set on the body portion 8 of the woman, as shown in Fig. 2.

On the forward end of the bicycle and below the handle is secured a lantern 9, having 35 a stone 10 inserted on the side.

No claim is made to the configuration of a woman upon a bicycle, but the invention is limited to the figures of the woman and the bicycle covered with small circles, as shown. 40

Having thus described my design, what I claim as new is—

The design for a brooch or pin, substantially as shown and described.

In testimony that I claim the invention set forth above I have hereunto set my hand this 16th day of October, 1895.

SAUL PRAGER.
